UNITED STATES PATENT OFFICE.

NORMAN J. WESTHAVER, OF CAMBRIDGE, MASSACHUSETTS, ASSIGNOR TO GEORGE H. MAXWELL, OF PHOENIX, ARIZONA.

SHOE-BOTTOM-FILLING MACHINE.

Application filed July 1, 1924. Serial No. 723,574.

This is an improvement on the type of shoe-bottom filling machine shown in the application of George H. Maxwell 560,800 (original filed September 14, 1921) 5 and 656,496 filed August 9, 1923, which are now respectively Patents 1,512,229 and 1,558,699. Referring particularly to the latter, it has been found difficult in practice to get the proper feed level for the water. 10 Also, in starting the machine in the morning in the shoe factory, the sudden high heat tends to cause the water to blow out or flow back from the steam generator and overflow the cup or water seal 29 in one 15 direction and to force out the collected condensation in a flood in the opposite direction into the reservoir, thereby flooding the filler with water instead of steam. Accordingly the present invention aims to remove 20 the foregoing three difficulties besides introducing further advantages, such as providing improved heat distribution, preventing the stoppage of water flow by the steam pressure in the generator and insuring water 25 circulation, preventing the tendency to form a steam pocket with explosions or pounding, facilitating the cleaning out of sediment, obviating the liability of the boiler warping and cracking, avoiding the warping 30 of the work-basin, and other advantages which will appear in the course of the following description.

The embodiment of the invention herein shown especially adapts the machine to electricity, a radiant or open electric unit being preferably provided.

In the drawings in which I have shown the preferred embodiment Fig. 1 is a longitudinal vertical section, parts being broken away; Fig. 2 is a view partly in top plan, broken away, and partly in horizontal section; Fig. 3 is a rear elevation, the water supply tank and contained parts being omitted; and Fig. 4 is an enlarged detail 45 in side elevation and partly in section of a portion of the boiler or steam generator.

In the preferred embodiment of my invention I employ substantially the same work-basin, herein designated as 1, as in the before mentioned application Serial No. 656,496, (Patent 1,558,699) reservoir 2, heat radiators or flues 3, dry heat chamber 4 providing a heat jacket 5 extending around

the reservoir and a jacket 6 around the work-basin, the aforesaid apparatus having its base or bottom plate 7 mounted on the upper end of a pedestal 8. Also in practice the machine has the same inclined shelf, roll and knife block as in said application, but not herein shown. At the rear is substantially the same water tank 9 as in said application, having an internal air pipe 10 extending into a water cup or water seal 11 for the delivery thereinto of water through any suitable pipe or outlet, herein shown as a pet cock 12, said tank being pivoted at 13 on brackets 14 secured at 15 adjustably if desired by set screws 16 at the back of the machine, Fig. 3. The pivot 13 is back far enough to insure stability against accidental tipping, to eliminate the necessity of a latch or lock to hold it upright, to permit free swinging over clear of the reservoir for filling purposes, and to give strength of bracing, while holding the tank against removal or against being lifted off. Besides the aforesaid advantages, the pivoting of the tank, as distinguished from being either fixed or bodily and directly removable, permits automatic constructions used in this type of shoe-bottom filling machine. When inverted, the tank 9 is filled through the opening or filling closure 90, the cap 91 being first unscrewed, but the tank is always otherwise closed except for the air inlet pipe 10 whose lower sealed end in the cup 11 determines the water level of the automatic delivery, and except for the pet cock 12 or other water discharge or delivery device. The cup or water seal 11 is provided with a strainer 17, and at its bottom is connected by a feed pipe 18, 19, 20, 21, 22, 23 to the front lower end of a boiler or steam generator 24. Beneath the latter is the heating element of any suitable kind, shown as an electric unit 25, carried in a clamping band or frame 26 supported underneath by a stand 27 and at its front end secured to the back side 28 of a removable switch and switch box 29. This unit and its connections are the same as in the last mentioned application excepting that they are inclined as shown best in Fig. 1 for a purpose which will presently be described. The boiler or steam generator 24 consists of a transverse pipe header or water container 30 and a

plurality of separate pipes, three thereof being herein shown and marked in Fig. 2 as 24, 24^a, 24^b respectively screwed into the header 30 at their forward ends and into oblique elbows 31 at their upper ends whence smaller pipes 32 lead up to a relatively large transverse distributor pipe or steam collector and distributor 33. From the steam distributor pipe 33 extend individual steam discharge pipes 34 discharging into the respective flues 3 and secured by a steam tight joint by any suitable means as by nuts 35 to the back 36 of the flue and the adjacent inclined back 37 of the reservoir. The pipe 33 is preferably slightly inclined from horizontal as best shown in Fig. 3 and at its lower or left hand end as there shown has a small outlet pipe 38 connected by an elbow 39 and nipple 40 to the vertical pipe 20 at whose lower end a mud drum or cup 41 to collect sediment is provided having a clean-out cap 42 at its lower end, a similar clean-out 41^a, 42^a, being preferably provided at the lowest front part.

One great difficulty with the previous steam generator (Serial No. 656,496 now Patent 1,558,699) has been its tendency to collect sediment rapidly and then of course cause various troubles and dangers and cease to operate. I obviate all these difficulties by providing a generator made up of pipes and in a circuit with the water entering at one end and leaving as steam at the opposite end, so that a swift flow is induced and a constant circulation and hence the sediment cannot lodge in quantity. The entire pipe system is so positioned and built as to tend to drain to the points 41 or 41^a or both. As the water enters the hot-air chamber it is given a preliminary heating by being caused to traverse the length of the chamber before entering the generator so that it is already hot when it enters the inlet end 30 of the steam generator. This economizes heating current. Preferably also this water-supplying pipe is inclined forward and downward, partly for proximity to the heater but chiefly to provide a water pocket and stronger barrier against a sudden back flow of steam in the wrong direction. The inlet end 30 is a trifle lower where the water enters so as to facilitate the flow of steam upward, or in other words the bubbles of steam readily travel rearward along the pipes without tendency to blow out the water. In the previous construction of Patent 1,558,699 there was a liability to rush the water in a flood all out of the boiler and then a comparatively small amount of water, too small for the requirements of the reservoir, would occupy the boiler and being converted into steam would cut off the intended free entrance of more water, at least in the amount needed. This was aggravated by the fact that the water entered the boiler

at the same end from which the steam left. My construction insures the even, unidirectional flow of both water and steam, retards the tendency to blow or rush the water along with the steam, and assures a steadier and more even flow of water to the apparatus. Moreover the inlet end 30 is the cool or cooler end, being arranged to admit the water at a point somewhat away from the direct impact of the radiant heat, the water inlet to the header 30 and the adjacent end of the generator 24 being located beyond the direct and intense influence of the unit 25. By inclining the heating unit the heat tends to flow upward and rearward, accelerating the heating efficiency of steam flow and production and providing the desired higher dry heat around the reservoir rather than around the work-basin, where a lower heat is preferable. The purpose of the still greater or steeper incline of the pipes 32 to a relatively upright position is to check any rush of water and cause it to flow back, so that even at the start of the apparatus there is very little water actually pushed up with the steam, and is to further constitute a water equalizing space to cooperate with the automatic water level supply (10, 11, 12, etc.) in aiding in maintaining the desired water level in the generator. This equalizing space and the generally inclined position of the generator obviate the nicety or fineness of adjustment previously necessary in the cup 11. The pipes 32 being relatively small tend still further to throttle or retard any sudden uprush of water at the start. But any water that might be pushed up by a sudden expansion and rush of steam is caught by the large pipe 33 as also any condensation when the machine is first started and all runs back to the inlet pipe. The pipes 32 are not opposite the discharge pipes 34 and hence any actual water from the former sprays against the opposite wall of the collector pipe 33 and then flows naturally down its inclined length to the outlet pipe 38. The pipes 32 preferably enter the pipe 33 above the bottom as viewed Fig. 4 and project appreciably so as not to interfere with the free flow downward of any collected water and so as to deliver the steam above any such flowing water. A further important advantage of my type and arrangement of steam generator is that it obviates the fine adjustment of the water level which is necessary in the machine of Patent 1,558,699. By the inclines explained a wider range of water level is practicable and the delicate (and often difficult) adjustment becomes unnecessary. In said previous machine the water seal or cup 11 would have its contents blown out by the steam if the apparatus was started cold on "high" especially if the reservoir was al-

ready full of filler. My construction obviates this. There is no forward flooding at the start and no rearward blowing out, and there is good heat distribution. A further feature of my invention consists of a heat distribution plate 43 clamped rigidly in place by any suitable means as a clamping bolt and bar 44. This prevents burning on the bottom, permits higher heat with safety, and being inclined cooperates with the inclined heating unit to promote the rapid rearward heat circulation previously mentioned. Holes 45 let in sufficient air to aid in this circulation. An asbestos cement bottom 46 is preferably provided. Also as this machine is operated at a high heat so that the upper end of the inclosure for the hot air space 6 would be liable to burn the operator's hands, I provide a special rim construction shown as a half round rim 47 secured at its ends or at least at its corners 48 by any suitable means as by being sweat-ed in place or soldered or riveted and thence sprung across the front away from the adjacent metal as shown in Fig. 1 so as to form an air space 49 for the free circulation of external air backward or forward beneath said rim, thereby keeping the same sufficiently cool to constitute a protector for the workman. A usual slide door 50 closes the front of the reservoir being operated by a handle 51 and provided with a latch 52 to catch over the projecting upper edge 53 of the upper part 54 of said slide door and to operate as described in said last mentioned application. The reservoir is closed by a cover 55 hinged at 56 to swing back against a stop 57. The flues 3 have a protector or guard strip 58 to prevent the operator accidentally injuring the flues with his knife or spatula in the normal use of the machine. A relatively large opening and a removable plate or door 59 at the back affords access to the steam generator and piping and for the removal or insertion of the latter. And for convenience of separate disconnection, cleaning, independent replacement, etc., I provide unions or couplings 60, 61, 62. For example if one of the pipes of the generator 24 gets stopped or cracks it may be separately removed by simply disconnecting its coupling 61 and then unscrewing the pipe from the header 30. After cleaning it, the pipe is readily put back again in the same manner.

In use the tank 9 having been swung over on its pivot 13 and filled at 90 with water is closed by cap 91 and turned back and the pet cock 12 opened which fills the boiler or steam generator 24 to the level determined by the air pipe 10 and thereupon the current is turned on at high and the water in the boiler is quickly turned into steam. Because of the pipe construction and the inclined position of the parts very little if any

adjustment of the water tank 9 is required in first setting up the machine, as the water circulation is continuous and free because of the pipe construction and there will always be a reasonable amount of water inside the machine available for steam purposes because of the inclined arrangement. Also because of the inclination of the pipe 22 there will always be a considerable body of water below the water container pipe 30 to resist any tendency of the suddenly formed steam to flow or drive backward, and this will tend to compel the steam to go in the opposite or upward direction, which because of the inclined arrangement of the steam generator is the natural and intended direction of steam discharge. As, however, the steam meets the considerably inclined or oblique and reduced-size pipes 32 any water which is being carried along or pushed along with the steam receives a physical check and tends to stop and flow backward into the boiler proper. But if any water or condensation should get up into the steam distributor and water collector pipe 33 it will naturally flow down as indicated in Fig. 4 and out through the pipe 38 and back into the delivery pipe 22. Upon first starting the machine it is probable that more or less water keeps up this circuit until the whole machine gets thoroughly hot and the filler which has been placed in the filler container or reservoir 2 gets melted and thoroughly permeated with the heat and steam. The steam is discharged from the distributor 33 through the nozzles 34 into the corresponding plurality of flues or heat radiators 3 provided therefor and said steam escapes at the front lower ends of said flues into the bottom portion of the filler mass, tending to make the latter loosen and drop downward by the melting disintegration and gravity. As soon as the filler has become sufficiently softened, usually requiring only a few moments, the operator raises the slide door 50 as far as desired and pokes out into the work-basin such an amount as he requires for immediate use and proceeds to fill the shoe-bottoms in the usual manner.

It is desirable that all portions of the machine shall be reasonably hot but the reservoir and rear portion of the machine should be the hottest and this is brought about largely by the interposition of a heat distribution plate 43 which prevents the heat going straight up from the unit 24 so as to strike directly against the bottom of the work-basin and reservoir and causes the heat to gather around the individual pipes of the boiler 24 and mostly follow lengthwise of the latter towards the rear, some of the heat going laterally of course and forwardly in the spaces 5 and 6. The plate 43 quickly becomes highly heated and thereafter constitutes a heat radiant or radiating plate

for giving a uniform heat directly to the bottoms of the work-basin and reservoir while at the same time preventing any localized heat in any one or more spots which 5 would inevitably tend to burn the filler and ruin the said bottom.

As already stated, my invention is not limited in all respects to the precise combination and embodiment shown, but is capable of a wide range of embodiments, combinations and sub-combinations as will be more evident from the claims hereinafter contained.

What I claim is:

1. In a machine of the kind described, the combination with a filler softening reservoir adapted to handle shoe-bottom filler which prior to use is normally self-sustaining but sluggishly fluid under moderate heat, of a heating unit or source of heat, a closed steam generator in the influence of said unit, said generator being formed of separated pipes, and means for delivering the steam from said generator into the filler within said reservoir.

2. In a machine of the kind described, the combination with a filler softening reservoir adapted to handle shoe-bottom filler which prior to use is normally self-sustaining but sluggishly fluid under moderate heat, of a heating unit or source of heat, a closed steam generator in the influence of said unit, said generator being formed of separated pipes arranged to compel circulation and independently removable, and means for delivering the steam from said generator into the filler within said reservoir.

3. In a machine of the kind described, the combination with a filler softening reservoir adapted to handle shoe-bottom filler which prior to use is normally self-sustaining but sluggishly fluid under moderate heat, of a heating unit or source of heat, a closed steam generator in the influence of said unit, said generator being formed of separated pipes, an upwardly inclined pipe outlet for the steam adapted to retard an upward flood of water, and means for delivering the steam from said generator into the filler within said reservoir.

4. In a machine of the kind described, the combination with a filler softening reservoir adapted to handle shoe-bottom filler which prior to use is normally self-sustaining but sluggishly fluid under moderate heat, of a heating unit or source of heat, a closed steam generator in the influence of said unit, said generator being formed of separated pipes, an upwardly inclined pipe outlet for each of said separate pipes for the delivery of steam and adapted to retard an upward flood of water, and means for delivering the steam from said generator into the filler within said reservoir.

5. In a machine of the kind described, the combination with a filler softening reservoir adapted to handle shoe-bottom filler which prior to use is normally self-sustaining but sluggishly fluid under moderate heat, of a heating unit or source of heat, a closed steam generator in the influence of said unit, said generator being formed of separable pipes, an upwardly inclined pipe outlet for the steam adapted to retard a forward flood of water, said inclined pipe being made in two parts separately coupled to permit of independent removal and inspection without removing the pipes of the generator, and means for delivering the steam from said generator into the filler within said reservoir.

6. In a machine of the kind described, the combination with a filler softening reservoir adapted to handle shoe-bottom filler which prior to use is normally self-sustaining but sluggishly fluid under moderate heat, of a heating unit or source of heat, a closed steam generator in the influence of said unit, a steam discharge adjacent one end of said generator arranged to deliver steam into the filler within said reservoir, and a water supply entering at the opposite end of said generator in cooperation with the steam production and discharge to produce in normal operation a unidirectional flow of both the water and steam.

7. In a machine of the kind described, the combination with a filler softening reservoir adapted to handle shoe-bottom filler which prior to use is normally self-sustaining but sluggishly fluid under moderate heat, of a heating unit or source of heat, a closed steam generator in the influence of said unit, a steam discharge adjacent one end of said generator arranged to deliver steam into the filler within said reservoir, and a water supply entering at the opposite end of said generator in cooperation with the steam production and discharge to produce in normal operation a unidirectional flow of both the water and steam, said inlet and the adjacent end of the generator being located out of the direct and intense influence of said unit.

8. In a machine of the kind described, the combination with a filler softening reservoir adapted to handle shoe-bottom filler which prior to use is normally self-sustaining but sluggishly fluid under moderate heat, of a heating unit or source of heat, a closed steam generator in the influence of said unit, a steam discharge adjacent one end of said generator arranged to deliver steam into the filler within said reservoir, and a water supply entering at the opposite end of said generator in cooperation with the steam production and discharge to produce in normal operation a unidirectional flow of both the water and steam, said generator being inclined slightly upward from its water inlet

end to facilitate the prompt and free flow and ascent of the steam and promote a natural halting of the water in the generator while being converted into steam.

5 9. In a machine of the kind described, the
combination with a filler softening reservoir
adapted to handle shoe-bottom filler which
prior to use is normally self-sustaining but
sluggishly fluid under moderate heat, of a
10 heating unit or source of heat, a closed steam
generator in the influence of said unit, a
steam discharge adjacent one end of said
generator arranged to deliver steam into the
filler within said reservoir, and a water sup-
15 ply entering at the opposite end of said gen-
erator in cooperation with the steam pro-
duction and discharge to produce in normal
operation a unidirectional flow of both the
water and steam, and an overflow pipe at
20 the steam end of the generator for draining
off surplus water.

144 70 75 80 85 90

13. In a machine of the kind described, the
combination with a filler softening reser-
voir adapted to handle shoe-bottom filler
which prior to use is normally self-sustain-
ing but sluggishly fluid under moderate heat,
of a heating unit or source of heat, a closed
steam generator separated from but in the
influence of said unit, an automatic water
level supply for said generator and means
for discharging steam from said closed gen-
erator within the filler in said reservoir, a
portion of said generator being close to and
substantially parallel to said unit and more
nearly level than another portion of said
generator, and said other portion of said

10. In a machine of the kind described, the combination with a filler softening reservoir adapted to handle shoe-bottom filler which prior to use is normally self-sustaining but sluggishly fluid under moderate heat, of a heating unit or source of heat, a closed steam generator in the influence of said unit, a steam discharge adjacent one end of said generator arranged to deliver steam into the filler within said reservoir, and a water supply entering at the opposite end of said generator in cooperation with the steam production and discharge to produce in normal operation a unidirectional flow of both the water and steam, and an overflow pipe at the steam end of the generator and above the main level of the generator for draining off surplus water.

25 generator, and a water level portion of said generator extending at an angle to said more level portion, to cooperate with said automatic water level in providing a large range of water level capacity for the generator in use. 90

30 14. In a machine of the kind described, the combination with a filler softening reservoir adapted to handle shoe-bottom filler which prior to use is normally self-sustaining but sluggishly fluid under moderate heat, of a heating unit or source of heat, a closed steam generator in the influence of said unit, means 95 for delivering steam from said generator into the filler in said reservoir, and water withdrawing means operating in connection with all the aforesaid for preventing water contained in said generator from being pushed or flooded along with said steam into 100

35

40 Surplus water.

41 11. In a machine of the kind described, the combination with a filler softening reservoir adapted to handle shoe-bottom filler which prior to use is normally self-sustaining but sluggishly fluid under moderate heat, of a heating unit or source of heat, a steam generator in the influence of said unit, a water supply for delivering water to said generator, means for delivering steam from said generator into the filler within said reservoir, and an overflow pipe opening from above the main water level of the generator for draining off surplus water and preventing said water from interfering with the proper action of the steam on the filler in the reservoir.

12. In a machine of the kind described, the combination with a filler softening reservoir adapted to handle shoe-bottom filler which prior to use is normally self-sustaining but sluggishly fluid under moderate heat, of a heating unit or source of heat, a closed steam generator in the influence of said unit, means for delivering steam from said generator into the filler within said reservoir, means for delivering water into said generator, and means for driving the steam and water into the reservoir, the steam and water being pushed or flooded along with the steam into the reservoir under severe driving heat of said unit.

16. In a machine of the kind described, the combination with a filler softening reservoir adapted to handle shoe-bottom filler which prior to use is normally self-sustaining but sluggishly fluid under moderate heat, of a heating unit or source of heat, a closed steam generator in the influence of said unit, means for delivering steam from said generator into the filler within said reservoir, means for delivering water into said generator, and means for driving the steam and water into the reservoir, the steam and water being pushed or flooded along with the steam into the reservoir under severe driving heat of said unit.

6
of said unit, a steam discharge adjacent one end of said generator arranged to deliver steam into the filler within said reservoir, and a water supply entering at the opposite end of said generator, and an overflow pipe connecting into the discharge end of the generator for withdrawing surplus water and preventing its being pushed or flooded along with said steam into the 10 reservoir under severe driving heat of said unit.

17. In a machine of the kind described, the combination with a filler softening reservoir adapted to handle shoe-bottom filler which prior to use is normally self-sustaining but sluggishly fluid under moderate heat, of a heating unit or source of heat, a closed steam generator in the influence of said unit, a steam discharge adjacent one end of said generator arranged to deliver steam into the filler within said reservoir, and a water supply entering at the opposite end of said generator, and an overflow pipe connecting into the discharge end of the generator, and thence back into said water supply for withdrawing surplus water from the generator.

18. In a machine of the kind described, the combination with a filler softening reservoir adapted to handle shoe-bottom filler which prior to use is normally self-sustaining but sluggishly fluid under moderate heat, of a heating unit or source of heat, a closed steam generator in the influence of said unit, said generator being located beneath the reservoir and above said unit, and a heat distribution plate located between the generator and the reservoir for spreading and equalizing the heat on the bottom 40 of the reservoir.

19. In a machine of the kind described, the combination with a filler softening reservoir adapted to handle shoe-bottom filler which prior to use is normally self-sustaining but sluggishly fluid under moderate heat, of a heating unit or source of heat, a closed steam generator in the influence of said unit, said generator being located beneath the reservoir and above said unit, and a heat distribution plate located between the generator and the bottom of the reservoir for spreading and equalizing the heat on the bottom of the reservoir, said plate having a slight air space between it and said bottom.

20. In a machine of the kind described, the combination with a filler softening reservoir adapted to handle shoe-bottom filler which prior to use is normally self-sustaining but sluggishly fluid under moderate heat, of a heating unit or source of heat, a closed steam generator in the influence of said unit, said generator being located beneath the reservoir and above said unit, and a heat distribution plate located between

the generator and the bottom of the reservoir for spreading and equalizing the heat on the bottom of the reservoir, said plate being spaced from said bottom a short distance and inclined upwardly toward the rear 70 for promoting a rearward flow of the heat.

21. In a machine of the kind described, the combination with a filler softening reservoir adapted to handle shoe-bottom filler which prior to use is normally self-sustaining but sluggishly fluid under moderate heat, of a heating unit or source of heat, a closed steam generator in the influence of said unit, said generator and said unit being inclined upwardly toward the rear 80 for causing higher heating efficiency toward the rear than the front of the machine.

22. In a machine of the kind described, the combination with a filler softening reservoir adapted to handle at high heat shoe-bottom filler which is normally slowly penetrative by heat and liable to burn at high heat, of a heating unit or source of heat for softening said filler, and means, including a water supply tank, for supplying 90 moisture to the filler, said tank being pivotally mounted to tip with relation to said reservoir.

23. In a machine of the kind described, the combination with a filler softening reservoir adapted to handle at high heat shoe-bottom filler which is normally slowly penetrative by heat and liable to burn at high heat, of a heating unit or source of heat for softening said filler, a steam generator in 100 the influence of said unit for facilitating the safe handling of said filler under said heat, a water supply tank for supplying water to said steam generator, and an automatic water level control and connections to said 105 generator for automatically maintaining desired water supply to the generator in accordance with the requirements of the filler in the reservoir, including a water seal cup, 110 an air pipe opening at one end in said cup and at the other end in the tank above the normal water level, and a water delivery from the tank into the cup.

24. In a machine of the kind described, the combination with a filler softening reservoir 115 adapted to handle at high heat shoe-bottom filler which is normally slowly penetrative by heat and liable to burn at high heat, of a heating unit or source of heat for softening said filler, a steam generator in the 120 influence of said unit for facilitating the safe handling of said filler under said heat, a water supply tank for supplying water to said steam generator, and an automatic water level control and connections to said 125 generator for automatically maintaining desired water supply to the generator in accordance with the requirements of the filler in the reservoir, including a water seal cup, 130 an air pipe opening at one end in said cup 135

and at the other end in the tank above the normal water level, and a manually controlled water delivery from the tank into the cup.

- 5 25. In a machine of the kind described, the combination with a filler softening reservoir adapted to handle at high heat shoe-bottom filler which is normally slowly penetrative by heat and liable to burn at high
10 heat, of a heating unit or source of heat for softening said filler, a steam generator in the influence of said unit for facilitating the safe handling of said filler under said heat, a water supply tank for supplying water to
15 said steam generator, and an automatic water level control and connections to said generator for automatically maintaining desired water supply to the generator in accordance with the requirements of the filler
20 25 in the reservoir, including a water seal cup having a strainer for the water passing through it, an air pipe opening at one end in said cup and at the other end in the tank above the normal water level, and a water delivery from the tank into the cup.

26. In a machine of the kind described, the combination with a filler softening reservoir adapted to handle shoe-bottom filler which prior to use is normally self-sustaining but sluggishly fluid under moderate heat, of a work-basin extending forward from said reservoir and having a top rim liable to become highly heated, and a protecting rim arranged to protect the top edge of said hot
30 rim and having portions raised out of contact with the hot rim so as to permit a cooling flow of air beneath the same for the protection of the operator.

27. In a machine of the kind described, the combination with a filler softening reservoir adapted to handle shoe-bottom filler which prior to use is normally self-sustaining but sluggishly fluid under moderate heat, of a heating unit or source of heat, a closed
40 steam generator in the influence of said unit, arranged to deliver steam into the filler in
45

said reservoir, means to deliver water into said generator, and a clean out settling chamber connecting with said generator for collecting sediment from the generator. 50

28. In a machine of the kind described, the combination with a filler softening reservoir adapted to handle shoe-bottom filler which prior to use is normally self-sustaining but sluggishly fluid under moderate heat, of a 55 heating unit or source of heat, a closed steam generator in the influence of said unit, arranged to deliver steam into the filler in said reservoir, means to deliver water into said generator, and an external clean out settling 60 chamber connecting with said generator for collecting sediment from the generator.

29. In a machine of the kind described, the combination with a filler softening reservoir adapted to handle shoe-bottom filler which prior to use is normally self-sustaining but sluggishly fluid under moderate heat, of a 65 heating unit or source of heat, a closed steam generator in the influence of said unit, arranged to deliver steam into the filler in 70 said reservoir, means to deliver water into said generator, and a clean out settling chamber connecting with said generator extending down from the water inlet for collecting sediment from the generator. 75

30. In a machine of the kind described, the combination with a filler softening reservoir adapted to handle shoe-bottom filler which prior to use is normally self-sustaining but sluggishly fluid under moderate 80 heat, of a heating unit or source of heat, a closed steam generator in the influence of said unit, arranged to deliver steam into the filler in said reservoir, means to deliver water into said generator, and a clean out settling chamber connecting with said generator extending down from the lowest part of the reservoir for collecting sediment from the generator. 85

In testimony whereof, I have signed my name to this specification.

NORMAN J. WESTHAVER.
